UNITED STATES PATENT OFFICE.

WILLIAM S. HAMM, OF HUBBARD WOODS, ILLINOIS, ASSIGNOR TO THE ADAMS & WESTLAKE COMPANY, OF CHICAGO, ILLINOIS, A CORPORATION OF ILLINOIS.

SASH-BOLT.

1,150,186.

Specification of Letters Patent. Patented Aug. 17, 1915.

Application filed July 14, 1913. Serial No. 779,046.

To all whom it may concern:

- Be it known that I, WILLIAM S. HAMM, a citizen of the United States, and resident of Hubbard Woods, county of Cook, and State of Illinois, have invented certain new and useful Improvements in Sash-Bolts, of which the following is a specification, and which are illustrated in the accompanying drawings, forming a part thereof.
- 10 The invention relates to bolts for window sashes, and particularly to bolts associated with controlling mechanism secured to a cross-rail of the sash at a considerable distance from the side thereof.
- 15 The object of the invention is to provide a bolt which, while housed within a longitudinal aperture in the sash rail, may be withdrawn therefrom without removing the sash from its casing.
- 20 The invention consists of a flexible bolt associated with any suitable controlling mechanism, and is illustrated in the accompanying drawings, in which—

Figure 1 is a detail elevation of a sash and its casing, some parts being broken away; Fig. 2 is a detail of the bolt and one form of controlling mechanism; Fig. 3 is a detail of the bolt, two of its sections being shown as separated; and Fig. 4 is a longitudinal section, partly in elevation of the bottom portion of a sash, showing the invention applied to a metal sash.

The sash casing is represented at 10, and a sash at 11. The bolt 12 is housed within a horizontal aperture 13, formed in the lower rail of the sash, the forward end of the bolt preferably being inclosed within a bushing 14 of metal and being engageable with recesses, as 15, formed in the stile of the window casing.

The bolt 12 is flexible, this flexibility being provided for in the construction as illustrated by forming it of a plurality of sections, as 16, 17, 18, as many such sections being employed as may be necessary. The outer end of the bolt is associated with any suitable controlling mechanism, such as the casing 19, adapted to fit within a recess in the face of the sash rail and housing a pair of angle levers 20, 21, which engage a suitable stud, as 22, on the bolt, the levers being controlled by a reciprocable finger-piece 23, provided with a stem 24 for engaging the

free arms of the levers. Any suitable spring, as 25, is applied for normally holding the bolt in its advanced position. The aperture 13, within which the bolt is housed, is necessarily quite small, being large enough, however, to permit the bolt to play freely therein without friction. The bolt may be inserted into and removed from this aperture through the aperture within which the casing 19 is seated.

When the bolt is made of rigid sections pivotally united, these sections should be of slightly less length than the aperture for accommodating the casing 19, in order that as each section is withdrawn to the extent of its length the joint uniting it with the next section emerges from the aperture 13, 70 and consequently may be flexed.

While I have shown and described a jointed bolt, I do not desire to be limited thereto, as the invention is of sufficient scope to include any form of flexible bolt.

When the sectional bolt is applied to a metal sash, as 26, it is advisable to provide a tube, as 27, within which it may reciprocate. The tube is shown as having its outer end anchored in the edge wall 28, of the sash and its inner end anchored in a cross plate 29.

I claim as my invention—

1. In combination, a sash, spring-actuated bolt-controlling mechanism seated within an aperture in the bottom rail of the sash and remote from its end, a flexible bolt attached to the controlling mechanism and extending longitudinally through the sash rail out of alinement with the mouth of said aperture, and being withdrawable therefrom through the aperture.

2. In combination, a sash, spring-actuated bolt-controlling mechanism seated within an aperture in the bottom rail of the sash remote from its end, a tube leading from the aperture for the controlling mechanism to the end of the rail and being out of alinement with the mouth of said aperture, a flexible bolt attached to the controlling mechanism and reciprocating within the tube and being withdrawable therefrom through the sash aperture.

3. In combination, a sash bolt comprising a series of pivotally connected units, and a guiding tube within which the several sec-

tions of the bolt reciprocates in the normal action of the bolt.

4. In combination, a closure, a bolt comprising a series of pivotally connected units mounted in a guideway in said closure, operating mechanism for said bolt, said guideway being provided with an outlet out of

alignment therewith through which the bolt may be withdrawn and replaced without dismounting the closure.

WILLIAM S. HAMM.
